[57] CLAIM

I claim the ornamental design for a therapeutic lamp, as shown and described.

DESCRIPTION

FIG. 1 is a side view of a therapeutic lamp, showing my new design;

FIG. 2 is a front view thereof;

FIG. 3 is a side view thereof, opposite that shown in FIG. 1;

FIG. 4 is a back view thereof;

FIG. 5 is a top plan view thereof;

FIG. 6 is a bottom view thereof; and,

FIG. 7 is a perspective view thereof.

The handable apparatus shown in the drawings is a polarized light-radiating therapeutic lamp for biostimulating with polarized light. Said apparatus especially serves as a therapeutic lamp, by which a ray beam of polarized light is radiated with a defined intensity and wavelength.
